UNITED STATES PATENT OFFICE

VINCENT DE LISO, OF ASTORIA, NEW YORK, ASSIGNOR TO SAKS & CO., OF NEW YORK,
N. Y., A CORPORATION OF NEW YORK

DESIGN FOR A SHOE

Application filed May 14, 1931. Serial No. 39,845. Term of patent 3½ years.

To all whom it may concern:

Be it known that I, VINCENT DE LISO, a citizen of the United States and a resident of Astoria, Long Island, in the county of Queens, State of New York, have invented a new, original, and ornamental Design for Shoes of which the following is a specification, reference being had to the accompanying drawings, forming a part thereof:

Fig. 1 is a perspective view of the left side of a shoe, showing my new design; and Fig. 2 is a perspective view of the opposite side of the shoe.

I claim:
The ornamental design for a shoe as shown.
Dated May 11th, 1931.

VINCENT DE LISO.
